FIG. 1 is a first perspective view of a disc for an agricultural tillage implement showing our new design.

FIG. 2 is a second perspective view of the disc for an agricultural tillage implement shown in FIG. 1.

FIG. 3 is a third perspective view of the disc for an agricultural tillage implement shown in FIG. 1.

FIG. 4 is a fourth perspective view of the disc for an agricultural tillage implement shown in FIG. 1.

FIG. 5 is a first plan view of the disc for an agricultural tillage implement shown in FIG. 1.

FIG. 6 is a second plan view of the disc for an agricultural tillage implement shown in FIG. 1.

FIG. 7 is a side elevation view of the disc for an agricultural tillage implement shown in FIG. 1; and,

FIG. 8 is a cross-sectional view of the disc for an agricultural tillage implement shown in FIG. 1, viewed along section 8-8.

1 Claim, 8 Drawing Sheets
